UNITED STATES PATENT OFFICE.

FRANKLIN HARDINGE, OF CHICAGO, ILLINOIS, ASSIGNOR TO HARDINGE BROTHERS, INC., OF CHICAGO, ILLINOIS, A CORPORATION OF ILLINOIS.

OIL BURNER.

Application filed May 5, 1923. Serial No. 636,867.

My invention relates to improvements in oil burners, and is particularly concerned with improvements in that type of oil burner comprising a rotary tubular atomizer for atomizing oil.

The objects of my invention are—

First: To provide an oil burner comprising a rotary atomizer, and means for supplying oil to the lower end of said atomizer, the said means being located below the bottom of the fire box of the furnace so as to be removed as far as possible from the heat of the fire box, and positioned so that the air which is supplied to the spray of oil formed by the atomizer passes around the lower end of the atomizer at the point where the fuel is discharged into the atomizer so as to keep the temperature of these parts as low as possible;

Second: To provide an oil burner comprising an atomizer of improved construction;

Third: To provide an oil burner comprising a rotary spindle, an atomizer secured to one end of the spindle, and a pipe for supplying oil to said atomizer, the atomizer and the pipe being so arranged that the atomizer can be removed from the spindle without disturbing the means for supplying oil thereto;

Fourth: To provide an oil burner comprising a rotary atomizer, a stand pipe for supplying fuel to the lower end of said atomizer, said pipe ending in a tube which discharges the oil into the atomizer, the tube being constructed so as to offer as little resistance as possible to the movement of the atomizer;

Fifth: To provide an oil burner comprising a spindle, an atomizer carried by said spindle, means for driving said atomizer comprising two shafts, and means for coupling said shafts constructed and arranged so as to prevent the two shafts from becoming permanently secured together under long continued usage, and to make it possible to readily separate said shafts.

Other objects of my invention will appear as this description progresses, reference being had to the accompanying drawings, in which

Figure 1 is a vertical longitudinal section through a portion of a furnace and oil burner embodying my invention;

Figure 2 is an enlarged sectional detail

showing certain features of construction of my improved means for supplying oil to the atomizer;

Figure 3 is a transverse section taken on line 3—3 of Figure 2;

Figure 4 is a side elevation of the upper end of the stand pipe forming a part of my invention, and

Figure 5 is a vertical transverse section taken on line 5—5 of Figure 1.

Throughout the several views, similar reference characters are used for referring to similar parts, and the several sections are taken looking in the direction of the small arrows.

The embodiment of my invention, which I have illustrated herein, comprises a bed plate 10 which is preferably supported in a depression 11 in a cement floor, and a base plate 12 upon which is removably supported the head 13 which forms a support for the antifriction bearings 14 and 15. A hollow spindle 16 is rotatably mounted in the bearings 14 and 15, and has secured to its lower end the bevel pinion 17 which meshes with the bevel gear 18. The head 13 is hollow and forms a reservoir for oil for lubricating the bearings 14 and 15 and the contacting surfaces of the gears 17 and 18. The head also comprises a chamber 19 which communicates with the portion of the head housing the spindle 16, by means of an opening 20.

A stub shaft 21 has its inner end secured to the gear 18, and is journaled in a sleeve 22 rotatably mounted in the bearing 23, which is in turn mounted in the head. A passageway 24 formed in the upper side of the head above the sleeve 22 provides means for receiving a portion of the lubricant thrown upwardly by the gear 18, and carrying it to the contacting surfaces of the shaft 21, sleeve 22, and the bearing 23.

The outer end of the stub shaft 21 is reduced in cross section, as shown at 25, and the portion 26 thereof tapers inwardly for a purpose which will later be referred to. For driving the shaft 21, I provide the driving shaft 27, the inner end of which is reduced in cross section, as shown at 28, and an intermediate portion 29 of which tapers outwardly. To enable the driving shaft 27 to be easily attached to and detached from the stub shaft 21, I provide the coupling sleeve 30, the outer surface of which tapers outwardly. A pair of keys 31 and 32 located in

co-acting slots in the adjacent ends of the two shafts and in the sleeve 30 provide means for connecting the ends of the two shafts to the sleeve, and thus to each other.

6 I also make use of a set screw 33 for securing the sleeve 30 to the outer end of the stub shaft 21. The head is provided with a hollow tubular extension 34 for closing the coupling 30. The shaft 27 passes 10 through an opening 35 in one end of this tubular extension, and the lower side of this opening is beveled downwardly and inwardly, as shown at 36, to drain into the head any oil which may reach this opening.

15 I prefer to fill the passageway 24 with waste 37, and to mount a felt washer 38 upon the tapered portion 26 of the stub shaft. By the construction just described, I provide means for detachably connecting 20 the adjacent ends of the two shafts 21 and 27, and which means will always remain lubricated, thereby insuring the easy removal of the shaft 27 from the head so as to permit the latter to be removed and 25 replaced by another in case repairs thereto become necessary.

A portion of the oil passing through the passageway 24 and the waste connected therewith will find its way onto the tapered 30 portion 26 of the shaft 21. Due to the shape of this portion of the shaft, the oil will gradually travel outwardly under the influence of centrifugal force and find its way along the contacting surfaces of the sleeve 30, the two ends of the shaft, and the keys 31 and 32, thereby keeping these parts thoroughly lubricated. The washer 38 will prevent an excessive amount of lubricant from working outwardly along the 40 shaft 21, but if an excess of lubricant should collect in the coupling, the outwardly tapered portion 29 of the shaft 27 will tend to return this lubricant to the coupling, and if any lubricant should work outwardly 45 along this shaft, it will be thrown off by the shoulder 40 on the shaft 27 and returned to the head by the walls of the opening 35.

The tube 41 is mounted in the spindle 16 and carried by the screw threaded plug 50 42 mounted in the lower side of the head. This tube extends upwardly in the spindle 16 to a point adjacent the outer end of the spindle which is counterbored, as shown at 43. A thimble 44 having the reduced end 55 portions 45 and 46 is inserted in the bore of the spindle immediately below the counterbore 43 so that its outer reduced end 45 forms with the adjacent wall of the spindle an annular recess 47, and its inner 60 reduced end 46 projects into the upper end of the tube 41.

A tubular outwardly flaring atomizer 48 is secured to the upper end of the spindle 16 by means of a screw threaded connection 65 49. For convenience in manufacture, I have

illustrated this atomizer as being formed of two parts secured together by a screw threaded connection 50. The lower end of the lower section of the atomizer is preferably provided with facets 51 for co-acting 70 with the jaws of a wrench, by means of which the atomizer can be removed from the spindle. The spindle is also provided adjacent its outer end with facets 52 for receiving the jaws of a wrench 53, the handle of 75 which may be provided with an opening for receiving the pin 54 carried by a projection 55 formed on the head. In this manner, the spindle can be anchored while the atomizer is being unscrewed therefrom. 80

The upper end of the atomizer is provided with a plurality of radially extending fan blades 56, and projects through an air controlling ring 57 carried by the sleeve 58 and the neck ring 59 upon which the sleeve 58 is adjustably mounted. The details of construction of the ring 57, the sleeve 58, and neck ring 59 are clearly set forth and claimed in the co-pending application filed jointly in my name and that of Benjamin H. Connor, Case 1, of even date herewith, and further description thereof appears to be unnecessary. 90

For supplying oil to the atomizer 48, I provide a stand pipe 60 which is supported by the pedestal 61 and extends upwardly through the tube 41 and the thimble 44 in spaced relation thereto, so as to provide a passageway 62 for air. Fuel is supplied to the lower end of the stand pipe 60 100 through the pipe 63, which may be connected with any suitable source of oil under pressure.

The upper end of the stand pipe 60 is provided with a cap 64 which is preferably 105 threaded onto the upper end of the stand pipe, as shown in Figure 2. This cap is provided with an inner annular passageway 65 which communicates with openings 66 formed in the sides of the upper end of the stand pipe. Tubes 67, having their ends inserted in the cap 64, and communicating with the annular passageway 65, extend downwardly and into the annular space 47 formed between the spindle and the upper 110 reduced end 45 of the thimble 44. The lower ends of these tubes are flattened, as shown at 68, so that when the spindle and the atomizer secured thereto are rotating, the edges of these tubes will offer comparatively slight resistance to the movement of the spindle and atomizer, and also provide ample clearance between their ends and the adjacent wall of the spindle for the passage 115 of oil upwardly to the atomizer. 120

It sometimes becomes necessary to clean the interior surface of the atomizer described above by inserting a poker 69, or some other suitable instrument, in the atomizer and gradually drawing it upwardly 125

while the atomizer is in motion. To prevent this instrument from injuring the tubes 67, or becoming entangled with the upper end of the stand pipe, I provide the disc 70 5 which is mounted upon the upper end of the cap. This end of the cap is preferably formed with facets 71 for receiving a wrench so that the cap and the tube 67 may easily be removed, if necessary.

10 The construction just described is such that the atomizer 48 can be unscrewed and easily removed from the furnace without the necessity of disturbing the stand pipe or the means secured thereto for discharging fuel 15 into the atomizer. It will also be noted that the latter means are located at a distance considerably below the bottom wall 72 of the fire box of the furnace. This I have found to be of very considerable importance, be- 20 cause if the means for supplying fuel to the atomizer are located adjacent the discharge end of the atomizer, where they are exposed more or less to the heat of the fire box, there is a very considerable tendency for the 25 fuel to become carbonized and deposited upon these oil supply means, so that ultimately the burner is rendered inoperable. By placing these means well below the bottom wall of the fire box of the furnace, I 30 have found that there is very little tendency for the fuel to deposit thereupon, this apparently being due to two causes. In the first place, these means are located so that the heat from the fire box does not readily 35 impinge thereupon, and, in the second place, they are located in the current of air which is supplied to the spray formed by the atomizer, so that this current of air tends to keep these parts at a comparatively low 40 temperature.

I have not described the details of construction of the bed plate, base plate, and the head of this burner, because these features are all clearly described and claimed in 45 my copending application, Serial Number 572,455, filed July 3, 1922.

While I have described the details of construction of the preferred embodiment of my invention, it is to be clearly understood 50 that my invention is not limited to these details, but is capable of other adaptations and modifications within the scope of the ap- pended claims.

Having thus described my invention, what 55 I claim is:

1. An oil burner comprising a head having a hollow spindle rotatably mounted therein, a tube supported in said hollow spindle and extending upwardly to a point adjacent the upper end of said spindle, a thimble having reduced ends mounted in the upper end of said spindle, one end of said thimble projecting downwardly into said tube, and the other end of said thimble forming 60 an annular space between it and said

spindle, a stand pipe extending upwardly through said tube and said thimble and in spaced relation thereto to form an air passageway, a cap closing the upper end of said stand pipe and carrying a discharge tube extending downwardly into the annular space between the upper end of said thimble and said spindle, and a tubular outwardly flaring atomizer detachably secured to the upper end of said spindle. 75

2. An oil burner comprising a head having a hollow spindle rotatably mounted therein, a tube supported in said hollow spindle and extending upwardly to a point adjacent the upper end of said spindle, a thimble having one end projecting downwardly into said tube, and the other end of said thimble forming an annular space between it and said spindle, a stand pipe extending upwardly through said tube and said thimble and in spaced relation thereto to form an air passageway, a cap closing the upper end of said stand pipe and carrying a discharge tube extending downwardly into the annular space between the upper end of said thimble and said spindle, and a tubular outwardly flaring atomizer detachably secured to the upper end of said spindle. 80

3. An oil burner comprising a head having a hollow spindle rotatably mounted therein, a thimble arranged to form an annular space between it and said spindle, a stand pipe extending upwardly through said tube and said thimble and in spaced relation thereto to form an air passageway, a cap closing the upper end of said stand pipe and carrying a discharge tube extending downwardly into the annular space between the upper end of said thimble and said spindle, and a tubular outwardly flaring atomizer detachably secured to the upper end of said spindle. 95

4. An oil burner comprising a rotatable hollow spindle, a thimble arranged to form an annular space between it and said spindle, a stand pipe extending upwardly through said spindle and said thimble and in spaced relation thereto to form an air passageway, a discharge tube carried by said stand pipe and extending downwardly into the annular space between the upper end of said thimble and said spindle, and a tubular atomizer detachably secured to the upper end of said spindle. 110

5. An oil burner comprising a hollow spindle, a tubular atomizer carried by the upper end of said spindle, a stand pipe extending through said spindle in spaced relation to the walls thereof for forming an air passageway, a discharge tube carried by the upper end of said stand pipe for supplying oil to said atomizer nozzle, and a disc carried by the upper end of said stand pipe for protecting said discharge tube from injury by cleaning instruments inserted in said atomizer. 125

6. An oil burner comprising a hollow spindle, a tubular atomizer carried by the upper end of said spindle, a stand pipe extending through said spindle, a discharge tube carried by the upper end of said stand pipe for supplying oil to said atomizer nozzle, and means carried by the upper end of said stand pipe for protecting said discharge tube from injury by cleaning instruments inserted in said atomizer. 40
7. An oil burner comprising a hollow spindle, a tubular atomizer carried by the upper end of said spindle, a stand pipe extending through said spindle, a discharge tube carried by the upper end of said stand pipe for supplying oil to said atomizer nozzle, and means for protecting said discharge tube from injury by cleaning instruments inserted in said atomizer. 45
8. A fuel oil burner comprising a gear casing, a hollow vertical spindle journaled therein, a horizontal drive shaft therefor, gearing therebetween within the casing, a tube extending upwardly from the bottom of the casing and within the spindle and providing an upward air passage, the lower end of the tube being open to the atmosphere, a fuel feeding stand pipe extending upwardly through said tube, a tubular thimble member secured at a mid-point thereof to the inner wall of the spindle, the thimble above said securing forming with the inner wall of the spindle an annular trough, and below said securing inwardly overhanging the upper end of said tube, means above said securing for delivering fuel oil from said stand pipe to the inner wall of the spindle, and an outwardly flaring tubular atomizing nozzle secured to the spindle above said securing. 50
9. The combination with an oil burner comprising a rotary hollow vertical spindle carrying at its upward end an outwardly flaring atomizing nozzle, a lubricant containing casing within which the spindle is journaled, a horizontal drive shaft entering said casing for rotating the spindle, a tubular wall open to atmosphere at its lower end extending upwardly within the spindle and constituting an inner wall for the lubricant containing casing, a stand pipe extending upwardly through said tubular wall, means at the upper end thereof for delivering oil from the stand pipe to the inner surface of the atomizer,—of means for catching liquid fuel which may descend the inner walls of the atomizer, and for preventing such liquid fuel from entering said lubricant containing case, said means comprising a tubular member centrally arranged within the spindle at a spaced distance inwardly from the inner wall thereof, and means intermediate the ends of said member for securing it to said spindle to rotate therewith and constituting a partition between the spindle and the tubular member, the upper end of the tubular member forming between it and the spindle a liquid fuel receiving trough, and the lower end of the tubular member forming an inverted trough with the spindle which trough receives the upper end of said tubular wall. 55
